Frank Liebenow; Justin P. Miller

(57) **CLAIM**

I claim the ornamental design for a wire chase panel, as shown and described.

DESCRIPTION

FIG. 1 is a front view of a wire chase panel showing my new design;

FIG. 2 is a rear view thereof;

FIG. 3 is a left side view thereof;

FIG. 4 is a right side view thereof;

FIG. 5 is a top thereof;

FIG. 6 is a bottom view thereof;

FIG. 7 is a top perspective view thereof; and,

FIG. 8 is a bottom perspective view thereof.

The broken lines depicting a raised central ridge in FIGS. 1, 2, 5, and 7 are for the purpose of illustrating the unclaimed portions of the article and form no part of the claimed design.

The broken lines depicting oval openings in FIGS. 5-8 are for the purpose of illustrating the unclaimed portions of the article and form no part of the claimed design.

The broken lines depicting holes in FIGS. 5-8 are for the purpose of illustrating the unclaimed portions of the article and form no part of the claimed design.

1 Claim, 7 Drawing Sheets
